TAPE DISPENSER OR SIMILAR ARTICLE

Charles Castelli, New Brunswick, and Irvin J. Gershen, Hillside, N. J., assignors to Johnson & Johnson, a corporation of New Jersey

Application November 10, 1953, Serial No. 27,536

Term of patent 14 years

(Cl. D74—1)

Fig. 1 is an isometric view of a tape dispenser showing our new design;

Fig. 2 is a side elevational view thereof showing the side opposite to that shown in Fig. 1;

Fig. 3 is a front elevational view;

Fig. 4 is a rear elevational view;

Fig. 5 is a top plan view; and

Fig. 6 is a bottom plan view thereof.

We claim:

The ornamental design for a tape dispenser or similar article, substantially as shown.
